PROTECTIVE FOOTWEAR WITH ELASTIC CLOSURE BAND

Carey W. Johnston, Leonia, N.J.

Application May 11, 1948, Serial No. 26,292

1. Claim. (CL 36—4)

1

This invention relates to overshoes and boots of the type having a foot portion and a predominantly self-supporting leg covering portion, made of rubber or the like, to provide for the wearer protection against mud, water and weather.

Self-supporting boots or overshoes are usually constructed either to have a wide clearance between the leg portion and the leg to enable the article to be donned and removed, or alternatively, the article is provided with a closure to snug the leg portion against the leg. In either type of article, there remains a clearance between the top of the leg portion and the leg of the wearer which permits entry of water or other matter within the boot or shoe. If the boot is used for wading purposes, the entry of water is unobstructed if the water becomes too deep and the purpose of the boot is defeated. If it is used merely for weather protection, drip from rain coats or outer garments invariably enters the boot and becomes uncomfortable to the wearer.

It is an object of this invention to provide an article of footwear, such as a boot or overshoe which will be sealed at its upper portion around the leg of the wearer to prevent the entry of water or other undesirable material. It is a further object of the invention to provide a sealing means which will have a minimum effect in making donning or withdrawal of the article more difficult than it might otherwise be. Still another object is to provide a sealing means which will give minimum discomfort to the wearer and which will have no effect in obstructing blood circulation in the leg of the wearer. Still another object is to provide a sealing arrangement which, when the seal is not needed, may be rendered ineffective to enable circulation of air within the boot thus to avoid undue heating of the leg and foot of the wearer.

Other objects of the invention will become apparent in reading the annexed detailed description in connection with the drawings, which show several non-limiting embodiments of the invention and its utilization on footwear of various types. It is to be understood that the embodiments shown are not to be construed as limiting, except as limitations may be implied in connection with the claim forming a part of this specification.

In the drawings, in which similar reference characters represent similar parts, Fig. 1 is a side elevation of a boot, partly in section, and showing features of the invention;

Fig. 2 is an elevation showing boots similar in 55 out exerting great enough pressure to cause dis-

general to that represented in Fig. 1 and incorporating closure means to make possible more expeditious donning and withdrawal of the boots;

Fig. 3 is a fragmentary elevation of an alternative form of boot leg portion, partly in section to show features of the invention;

Fig. 4 is an elevation of boots of the type disclosed in Fig. 3 showing one in the sealing position of adjustment and another in the non-sealing position of adjustment;

Fig. 5 is an elevation of a boot leg portion, partly in section, showing an alternative arrangement; and

Fig. 6 is an elevation showing the boots of the type of Fig. 5 in use.

In several of the figures, the footwear of the invention include foot covering or shoe portions 10 which are of any appropriate configuration and preferably comprise rubber-like self-supporting yielding material, usually including a fabric base, of the type normally used in the construction of rubbers, galoshes, and boots. From the shoe portion 10 of the footwear a leg covering portion 12 extends upwardly, being of the same general character of material as is used for the foot covering portion 10, this material preferably comprising a rubber or rubber substitute material reinforced if desired with fabric.

Now referring particularly to Fig. 1 the boot leg portion 12 is constructed for a loose fit around the leg of the wearer to enable easy donning or withdrawal of the boot without closures or strap arrangements, and to terminate at its upper end below the wearer's knee. The clearance necessary for donning and withdrawal normally permits a wide gap to exist between the boot and the leg of the wearer, particularly at the top. This clearance permits the entry of water or other matter under certain conditions, to the great discomfort of the wearer. According to my invention, I provide a grommet or circlet 14 which is bonded as at 15 to the inside of the leg portion of the boot; this grommet preferably being constituted of sponge rubber or foam rubber. The grommet is made with sufficient thickness, represented by the character 16, to take up the clearance between the boot upper edge 15 and the leg of the wearer, along with sufficient added thickness so that a light pressure will be exerted by the grommet upon the leg of the wearer. The sponge or foam material is so chosen as to be readily yieldable so that it may adapt its configuration to the wearer's leg without exerting great enough pressure to cause dis-

comfort.

comfort or binding upon the wearer's leg and yet, with sufficient pressure to seal the top of the boot relative to the wearer's leg and to deny the entrance of moisture or foreign matter into the space which would otherwise exist between the boot and the leg. Sponge materials of rubber or rubber substitute, of the type described, are known in the art and may readily be made with varying degrees of yieldability and flexibility. Thus, one skilled in the art may choose that composition of sponge material which is best suited for the purpose herein disclosed.

In Fig. 2, substantially the same form of boot is shown as that of Fig. 1, except that a closure 18 such as a slide fastener, may extend from the top of the boot part way down the leg covering portion to ease the donning and withdrawal of the boot. In this embodiment, the leg covering portion 12 may be constructed to embrace the leg of the wearer more closely than would the boot of Fig. 1 since opening of the closure 18 makes unnecessary the wide clearance relationship which obtains in the case of Fig. 1. Further, in Fig. 2, the thickness of the grommet 14, which is split adjacent the closure opening, may be less than that of the arrangement of Fig. 1 since the clearance space between the top of the boot and the leg of the wearer would be less than in the case of Fig. 1.

There may be times during which sealing of the boot against the wearer's leg may be unnecessary whereupon it may be desirable to provide ventilation of the clearance space within the boot. To this end, as shown in Fig. 1, I provide a clip 20 in the form of a U-shaped member of metal or the like, which may be slid down over the top of the boot, to compress locally a portion of the grommet 14 thereby to form a vent between the space within the boot and the atmosphere. If desired, this clip may take the form of a decorative rosette 22 or the like so that the presence of the clip upon the boot will have aesthetic appeal.

Fig. 3 shows an alternative boot arrangement in which the yieldable self-supporting leg portion of the boot 12 has superimposed thereon a somewhat flexible top portion 24, the top 26 of which has a lesser periphery when unstretched than the diameter of the top 28 of the normal leg portion 12. The portion 24 may be fabricated separately and attached to the portion 12 by suitable cementing or vulcanizing. While the drawing shows the two portions continuous, it is to be assumed that there is a difference in the materials or arrangements thereof. The unstretched periphery of the uppermost portion 26 is preferably slightly greater than the periphery of the wearer's leg at the point where it would lie upon the leg, to avoid substantial restriction of the wearer's leg. The grommet 14 is secured to and within this uppermost portion 26 to provide a light seal against the wearer's leg as previously described. When sealing of the boot is unnecessary, or when donning or withdrawing of the boot relative to the leg and foot is accomplished, the elastic top portion 24 of the boot may be folded down over the flexible self-supporting portion 12 of the boot as shown in dotted lines, enabling full ventilation of the clearance space of the boot proper to the atmosphere and further enabling easy donning and withdrawal of the boot. When sealing of the boot against the wearer's leg may become necessary, as in a rain storm or in wading, the flexible boot portion 24 with the grommet 14 may be drawn up over the wearer's leg to afford sealing against the wearer's

leg and further to augment the length of the boot so that wading depth is increased.

Fig. 4 shows one boot on a wearer in sealing relation, and also shows the upper portion 24 of the other boot folded down and over the main boot portion to enable ventilation, donning, and withdrawal.

Figs. 5 and 6 show an alternative arrangement of the invention which, in effect, is a modification of the arrangement of Fig. 1. Herein, the grommet 14' of sponge rubber or the like is extended materially in an axial direction so that its length, axially, is considerably greater than the thickness of the material. This arrangement provides a substantially greater bearing surface of the sponge rubber material against the leg of the wearer, reducing the unit pressure of the grommet against the leg and thereby reducing its binding effect without interfering with its sealing effectiveness. Furthermore, in the boot of Figs. 5 and 6, the leg portion 12 of the boot proper is shown as being expanded, or having a somewhat funnel-like configuration at its upper portion 30, the grommet 14' being secured within the funneled upper portion 30. This arrangement may allow a somewhat trimmer appearance of a boot, particularly of a long boot which may extend to or beyond the knee, since the open space within the grommet, when the latter is compressed, during withdrawal or donning, occupies a portion of the funneled boot portion 30 and becomes substantially equal in its open area to the area lying within the walls of the boot portion 12. Thus, a relatively large volume of grommet material may be installed in the boot to provide effective sealing and greater yieldability in the grommet, without the need of enlarging the sectional area of the boot upper portion proper while still maintaining adequate ease for donning or withdrawal.

While the drawings and description cover footwear of less-than-knee height, the principles of the invention may also be applied to boots or waders which extend above the knee, and to other articles wherein light sealing engagement is desired between an article of apparel and a limb embraced thereby.

It is further to be noted that the grommeted boot herein described prevents flapping of its upper portion against a wearer's leg. Such flapping, besides being uncomfortable, causes unnecessary stocking wear and, at times, discoloration of stockings. Also, in cold weather, the grommet serves as a heat retainer preventing the escape of body heat from the boot. The grommet also serves to prevent constriction of a wearer's leg—a great advantage over prior boot closures embodying tightening straps or lacings. Such straps or the like are not wholly effective as seals, and cause added complication in donning or withdrawing the boot.

Though several embodiments illustrating the invention have been shown and described, it is to be understood that the invention may be applied in other and various forms. Changes may be made in the arrangements, without departing from the spirit of the invention. Reference should be had to the appended claim for definitions of the limits of the invention.

What is claimed is:

An article of flexible protective footgear comprising substantially inelastic self-supporting foot and upper portions, the upper portion being adapted to embrace the leg of the wearer, and a circular band of elastic yieldable impervious

foam-like material secured to the inner surface of said upper portion adjacent its top edge, said band being of a thickness to provide material elasticity, said band having a length in the direction of the axis of said upper portion substantially greater than the band thickness, and the part of said upper portion below said band being necked inwardly downwardly from a point immediately below said band to a lesser diameter than the part of the upper portion embracing said band, the band extending inwardly slightly beyond the inner face of the necked in portion.
